E. L. OGLE

FUSE

Filed Sept. 1, 1921

INVENTOR
Elmer L. Ogle
by Elmer L. Ogle Atty.

UNITED STATES PATENT OFFICE.

ELMER L. OGLE, OF CHICAGO, ILLINOIS, ASSIGNOR TO FEDERAL ELECTRIC COMPANY, OF CHICAGO, ILLINOIS, A CORPORATION OF ILLINOIS.

FUSE.

Application filed September 1, 1921. Serial No. 497,585.

To all whom it may concern:

Be it known that I, ELMER L. OGLE, a citizen of the United States, and a resident of Chicago, county of Cook, and State of Illinois, have invented certain new and useful Improvements in Fuses; and I do hereby declare that the following is a full, clear, and exact description thereof, reference being had to the accompanying drawings, and to the letters of reference marked thereon, which form a part of this specification.

This invention relates to overload circuit breakers, commonly known as fuses, and consists of the matters hereinafter described and more particularly pointed out in the appended claim.

The invention relates to a novel and improved fuse for use in multiphase circuits, which is adapted, upon an overload and resulting opening of the circuit of one phase, to open the circuit of the other phase or phases.

The improved fuse is generally of the construction described and illustrated in an application for patent (filed August 29, 1921, Ser. No. 496,207), and contains a renewable cartridge in which is a heating coil designed to be connected with the terminals of another circuit.

The object of the invention is to provide a simple and efficient device for connecting the heating coil of the fuse with the second circuit and at the same time produce a device of the kind which is cheap and economical to manufacture and is capable of ready and easy assembly.

The advantages of the invention will appear as I proceed with my specification.

In the drawings:

Figure 1 is a diagrammatic view, showing my improved fuse as applied and connected in a three-phase system.

Figure 2 represents an enlarged side elevation of the fuse, with part of the fuse body broken away near one end to show the cartridge.

Figure 3 is a fragmental longitudinal section through the fuse, greatly exaggerated.

Figure 4 is a section through Figure 3 in a plane indicated by the line 4—4 of Fig. 3.

Figure 5 is a perspective view of the two parts of the connecting device, as used when for "front connected" installation.

Figure 6 is a sectional view showing the

connecting device as when used with a "back connected" installation.

Referring now to that embodiment of the invention illustrated in the drawings: 10 indicates the improved fuse, which is of the knife blade type. Three such fuses 10, 10^a and 10^b are shown in the diagrammatic view of Figure 1, each connection in one of the mains 11, 11^a, 11^b of a three phase system, which are connected to a motor or other translating device indicated at 12. 15 Each fuse contains a heating coil connected in multiple (in shunt as illustrated) by conductors 13, 13—13^a, 13^a—13^b, 13^b to another circuit: the conductors 13, connecting the heating coil of the fuse block 10 to the main 11^a; the conductors 13^a, connecting the heating coil of the fuse block 10^a to the main 11^b; and the conductors 10^b, connecting the heating coil of the fuse block 13^b to the main 11. This is familiar 20 practice with fuse blocks of the kind.

The fuse itself comprises a fibre body 14 with metallic heads 15, 16, each carrying a blade contact 15^a, 16^a, and an enclosed cartridge 17 containing fusible bars, the "tell 25 tale tags" of which are indicated at 18, and a heating coil with terminals (not shown) connected to two spring contacts on the outside of the cartridge body, one of which contacts is shown exposed at 19. The construction of the fuse in these particulars is fully disclosed in the application above referred to and as the details of said construction form no part of the present invention they need not be more particularly described 30 here.

Terminals 20, 20 are provided on the outside of the body 14 of the fuse for connecting the contacts 19 of the heating coil of the cartridge with the conductors which connect 35 said heating coil with another circuit. Where said terminals are for "front connected" work, as shown in Figures 1 to 5, the terminal consists of a stud having a reduced, threaded end 21 of a length 100 slightly greater than the thickness of the wall of the fuse body, with a radial shoulder 22 at the top of the thread. The stud has a transverse bore 23, near its top, for the insertion of a conductor wire and is tapped 105 at the top to intersect said bore so as to receive a screw 24 adapted to engage and hold the wire conductor in place.

In the fibre body 14 of the fuse is tapped a hole, and an internally threaded thimble 25 is screwed into said hole, with its inner end extending beyond the inner surface of the tubular body of the fuse. The outer end 26 of the thimble, which is reduced in thickness, is turned down and riveted against the outer surface of the fuse body. The reduced threaded end 21 of the terminal 20 is screwed into the thimble until its shoulder 22 engages against the riveted end of the thimble, when its end will be flush with the inner end of the thimble, thus providing a contact surface for engagement with the spring contact 19 of the heating coil of the cartridge.

Such terminal device connection is also applicable for use with "back connected" work where a blade contact is used, such as described in Patent No. 1,485,703 granted to me on March 4, 1924. This is illustrated in Fig. 6, where 27 indicates the blade contact and 27^a, a threaded stud thereon. 28 indicates the internally threaded thimble, threaded into the body 14 of the fuse as before.

A terminal connection of the kind described is readily and cheaply manufactured and is manifestly adaptable for either "back connected" or "front connected" installation.

I claim as my invention:

In an electric fuse for use in multiphase circuits, in combination with a cylindrical fuse body and a removable cartridge containing a fusible element and a heating coil associated therewith, said cartridge having auxiliary contacts on the outside of its body connected to said heating coil, terminals on the cylindrical fuse body adapted to connect said auxiliary contacts with conductors outside of said fuse, each terminal consisting of a member adapted for connection with an outside conductor, said member having a reduced, threaded end, the fuse body being provided with a threaded hole, a tubular internally and externally threaded thimble engaged in the hole in said body and projecting beyond the body wall on one side and having its outer end turned down against the cylindrical outside surface of said fuse body to lock the thimble against turning with respect to said fuse body, and the reduced threaded end of said terminal member being screwed into said thimble with its end flush with the inner end of said thimble in position to engage said auxiliary contact.

In testimony that I claim the foregoing as my invention, I affix my signature, this 15th day of August, A. D. 1921.

ELMER L. OGLE.
